UNITED STATES PATENT OFFICE.

ROBERT A. LAIDLAW, OF SAN ANTONIO, TEXAS, ASSIGNOR OF ONE-FOURTH TO L. T. WRIGHT AND ONE-FOURTH TO J. T. HAILE, BOTH OF SAN ANTONIO, TEXAS.

BUILDING CONSTRUCTION.

Application filed February 4, 1927. Serial No. 165,955.

My present invention has reference to a building construction and my object is a provision in a building of simple but thoroughly effective means for supporting roofing, floors and sidings in a manner which will effectively strengthen as well as render the same soundproof, airproof, moisture proof and fireproof.

A further object is the provision in a building construction of fluted or corrugated sheets, of fireproof insulated material, carrying the superimposed loads, that have arranged thereover and secured thereto similar sheets of flat material which materially increases the strength of the corrugated or fluted sheets and provides a series of dead air spaces therebeneath providing a third insulating medium. To the flat sheets the finished roofing, flooring or siding is easily applied.

A still further object is a means for this purpose in which carrying members of fire proof insulating material are employed of such shape to carry the superimposed loads between the roof purlins, floor joist or girts as the case may be, the said members being fluted forming a series of V's and the connecting parts between the anglesides thereof being thickened to provide sufficient area in tension and compression to take care of stresses in said inner members that result from loads imposed thereon.

To the attainment of the above broadly recited objects and others which will present themselves as the nature of the invention is better understood, the improvement consists in the construction, combination and operative association of parts, a satisfactory embodiment of which is disclosed by the accompanying drawings.

In the drawings:

Figure 1 is a sectional view through the roof or floor portion of a building illustrating the application of my improvement thereon.

Figure 2 is a sectional view approximately on the line 2—2 of Figure 1.

Figure 3 is a fragmentary perspective view of the inner corrugated fireproof member employed.

Figure 4 is a sectional view through the floor or roof or side of a building.

Figure 5 is a view approximately on the line 5—5 of Figure 4.

Figure 6 is a perspective view of the inner member disclosed by Figures 4 and 5.

In Figures 1 and 2, of the drawings I have illustrated my improvement in connection with the roofing, flooring or siding of a building. The building may and preferably is of fire proof construction. The roof, floor or siding construction 4 is attached to the roof, floor or siding supports 2 by bolts, hooks or anchors 3. The finished inner surface is obtained by the usual method of using supports 1 between the roof, floor or siding supports 2 and upon which may be attached the inside finish.

In carrying out my invention I lay on the supports 2 sheets of corrugated or fluted fireproof insulating material. The corrugated or fluted sheets are arranged edge to edge and end to end and may be affixed to the supports 2 by means similar to the elements 3. Resting on the upper part of the corrugated or fluted sheets are flat sheets 7 of fire proof insulating material. At determined intervals there is passed through the flat sheets 7 rust proof screws, bolts or rivets 8 securely tying together the corrugated or flat sheets 5 and 6 to the flat sheet 7, and to which can be applied the roofing or floor finish 9. Preferably the corrugated fluted and flat sheets, which embody my invention are constructed of asbestos, cement but any other suitable insulating and fireproof material may be used. The corrugated or fluted sheets combined with the flat sheets provide dead air spaces between the roof or floor and render the latter both sound and moisture proof and provide a third insulating medium.

While I have illustrated the corrugated sheets disclosed in Figures 1 and 2, employed in connection with the roof or floor of a building, it is to be understood that this construction may be successfully employed upon sidings of buildings. However, in Figures 5, 6 and 7 I have illustrated a slightly modified form of the corrugated sheets. In these figures the sheets 13 have straight and thickened portions 14 connected by angle webs 15 of a less thickness than the parts 14. This fluted or corrugated sheet rests directly upon the floor joists 16 and is secured thereon in any suitable or designed manner. The upper thickened connected portions for the oppositely inclined or web portion 6 of the corrugated sheets may have at determined intervals openings therethrough for the reception of non-rust bolts, screws or rivets 17 that pass through flat sheets or sheets 18 of similar ma-

terial through the support 13. On the sheets 18 there are laid and secured floorings, roofings and siding.

The simplicity of my improvement and the advantages thereof will, it is thought, be perfectly apparent to those skilled in the art to which the invention relates, when the foregoing description has been carefully read in connection with the accompanying drawings

10 so that further detailed description is not believed necessary.

Having described the invention, I claim:—

In a building construction, a support, a corrugated sheet of fire proof material arranged over the support, and the side walls 15 provided by the corrugated sheet being of a less thickness than the connecting walls for said side members, and a sheet of fire proof material resting on the corrugated sheet and riveted to the upper walls of said corrugated 20 sheet.

In testimony whereof I affix my signature.

ROBERT A. LAIDLAW.
